MULTI-STAGE DRAG PUMP

Hugh MacInnes, Richmond Heights, Ohio, assignor to
TRW Inc., Cleveland, Ohio, a corporation of Ohio
Filed June 4, 1965, Ser. No. 461,415
12 Claims. (Cl. 103—108)

This invention relates generally to a so-called reentry compressor or fluid pump sometimes referred to as a drag pump and which is particularly characterized by a rotor having a central hub with a disk-shaped body and peripheral vanes on opposite axial sides thereof with an axial or radial through passage means formed in the disk-shaped body either with or without pumping vanes for interconnecting and staging the oppositely disposed vanes in series flow relation.

Fluid pumps which are commonly known as drag pumps, offer characteristics in a centrifugal compressor which fall somewhere between those of the positive displacement pump and the centrifugal pump. This means the single stage pump produces a medium pressure at the output when running at a medium speed, as compared with either of the other two types. Because of those characteristics and the fact that it is not a positive displacement pump, there are many applications where such a pump should do a good job and be economically feasible as compared to the other two types.

In some instances, it is desirable to have a discharge pressure in the same magnitude as the positive displacement pump while running in the same speed magnitude. In accordance with the principles of the present invention, such objective can be accomplished by placing additional stages on the drag pump without increasing the size and complexity of the pump by the means of internal passaging such as a passage formed by holes or apertures extending axially through the disk of the rotor and allowing the fluid to pass from a first stage on one side of the rotor to a second stage on the other side of the rotor. By virtue of such provision, the stages are interconnected and staged in series. It will be apparent that the staging arrangement thus contemplated would apply to drag-type turbines as well as to compressors since the general structural arrangement would be similar in both.

It is an object of the present invention, therefore, to provide a compressor means affording discharge pressures in the same magnitude as positive displacement pumps, but with a compressor means running in the same speed magnitude as a drag pump.

Another object of the present invention is to provide a so-called reentry-type compressor wherein multiple stages are interconnected through internal passages formed in the body of the rotor.

Another object of the present invention is to provide a staging arrangement for a fluid pump which avoids increase in size and complexity of the pump construction.

Many other features, advantages and additional objects of the present invention will become manifest to those versed in the art upon making reference to the detailed description which follows and the accompanying sheets of drawings in which a preferred structural embodiment of a reentry-type compressor is shown by way of illustrative example.

On the drawings:

FIGURE 1 is an end elevational view of a reentry compressor provide in accordance with the principles of the present invention;

FIGURE 2 is an end elevational view from an end opposite that shown in FIGURE 1 of the reentry compressor of the present invention;

FIGURE 3 is a cross-sectional view taken on line III—III of FIGURE 1;

FIGURE 4 is an elevational view of the inlet cover taken on the plane of line IV—IV of FIGURE 3;

2

FIGURE 5 is an elevational view of the inside of the outlet cover taken in the direction of the plane of line V—V of FIGURE 3;

FIGURE 6 is a fragmentary cross-sectional view taken on line VI—VI of FIGURE 5;

FIGURE 7 is an elevational view showing additional details of construction of the rotor;

FIGURE 8 is a fragmentary cross-sectional view taken on line VIII—VIII of FIGURE 7;

FIGURE 9 is a fragmentary cross-sectional view taken on line IX—IX of FIGURE 5;

FIGURE 10 is a cross-sectional view of an alternative form of construction wherein the intercommunication between the stages is formed by axial through holes in the hub of the rotor;

FIGURE 11 shows yet another embodiment of the present invention wherein the rotor is formed out of a thin sheet material such as sheet metal and wherein the intercommunication between the stages takes the form of radial openings including centrifugal vane pumping means for assisting the pumping action achieved by the pumping apparatus; and

FIGURE 12 is a fragmentary cross-sectional view taken generally on line XII—XII of FIGURE 11.

As shown on the drawings:

The pump of the present invention comprises a reentry compressor shown generally at 10. An inlet cover 11 has a flange 12 formed with a plurality of apertures 13 for receiving fastening means such as screws 14 for engaging correspondingly threaded openings 16 provided in a flange 17 of an outlet cover 18. Thus, the inlet cover 11 and the outlet cover 18 may be fastened together in order to form a casing for the compressor.

The inlet cover 11 is particularly characterized by a centrally disposed boss 19 having a bore 20 in which is received a sleeve 21 forming a pair of axially spaced races 22, 22 in which to journal a shaft 23. The shaft 23 is characterized by a pair of axially spaced grooves 24, 24 arranged to be disposed in register with the races 22, 22 and a plurality of shiftable elements such as bearing balls 26 are disposed between the races 22 and 24. The shaft 23 extends outwardly of the casing and has connected thereto a pulley 27, thereby to provide a connection to a motive source. The inner end of the shaft 23 is connected as at 28 to a rotor shown generally at 29.

As shown in FIGURE 2, the inlet cover 11 has formed on the outside face thereof a plurality of radially extending circumferentially spaced strengthening ribs 30 and there is also provided a pair of spaced bosses 31, 31 which may be used as pad mounts for the pump. At the upper portion of the inlet cover 11, there is formed a boss 32 having a flat face intersected by an inlet opening 33, to which face 32 may be connected an inlet adapter for connecting the inlet 33 to a source of fluid to be pumped.

Referring now to FIGURE 4, the inner face of the inlet cover 11 is shown as being characterized by a semi-toroidal circumferentially extending pumping duct 34 having an inner wall 36 and an outer wall 37, both of which are arranged in generally concentric relation to the axis of the pump, thereby to form a pumping duct which extends circumferentially from an end portion 38 to an opposite end portion 39. The end portion 38 is arranged just adjacent the inlet opening 33 and at the end portion 39, the inside face of the inlet cover 11 is characterized by a radially inwardly extending discharge passage 40.

The outlet cover 18, as shown in FIGURE 1, has a plurality of strengthening ribs 41 which extend radially outwardly from a center boss 42. On opposite sides of the boss 42 there is provided a pair of bosses 43, 43 each having a flat face 44, thereby to provide additional pad mounting means for the compressor.

At the upper portion of the outlet cover 18, there is

formed a boss 46 having a surface 47 by means of which an outlet adapter may be connected to an outlet opening 48 which intersects the surface 47.

Referring now to FIGURE 5, the inside surface of the outlet cover 18 is shown as being characterized by the formation therein of a semi-toroidal recess 49 having an outer wall 50 and an inner wall 51, both concentrically disposed relative to the pump axis. The recess 49 extends circumferentially from an end portion 52 disposed immediately adjacent the outlet opening 48 and the recess 49 extends to the opposite end portion 53. At the end portion 53, there is formed a radially inwardly extending inlet passage 54 which intersects an annular groove 56 spaced outwardly of a center boss 57.

Referring now to FIGURE 7 in conjunction with FIGURE 3, it may be noted that the rotor 29 may conveniently comprise two separate parts fastened together to form a single disk-shaped article, the two parts having a line of juncture shown at 60. The rotor 29 has a hub 61 in which the shaft 23 is connected as at 28 and a disk-shaped body extends radially outwardly from the hub 61 terminating in an enlarged peripheral portion 62.

The rotor 29 is particularly characterized by having formed therein semi-toroidal circumferentially continuous vane ducts on opposite axial sides thereof which are adapted to be disposed between the pumping ducts or recesses 34 and 49 respectively. In this connection, note that one face of the rotor 29 has a circumferentially extending recess formed therein which is identified at 63 including an inner wall 64 and an outer wall 65. That recess 63 confronts the recess 34 formed in the inlet cover 11.

In like manner, the other face of the rotor 29 has a semi-toroidal recess 66 formed therein having an outer wall 67 and an inner wall 68 and which recess 66 confronts the pumping duct 49.

In the course of fabrication, the rotor 29 is provided with a plurality of slots which extend transversely of the corresponding recesses 63 and 66 and which slots are more specifically identified in FIGURE 7 at 69. Received within each slot 69 is a vane 70, thereby disposing a plurality of vanes 70 in an annular row in circumferentially spaced relation so that all of the vanes 70, in the respective recesses 63 and 66, form a plurality of impeller pockets 71 adapted to be moved upon rotation of the impeller 29 within the casing formed by the inlet cover 11 and the outlet cover 18.

It may also be noted that the outlet cover 18 is particularly characterized by an axially extending portion 72 providing an inner axial wall 73 disposed adjacent the outer periphery of the rotor 29.

In accordance with the principles of the present invention, the oppositely disposed pumping ducts or runners 34 and 49 and the oppositely disposed vanes of the rotor 29 are interconnected for series staging relationship by means of a passage extending through the disk-shaped body portion of the rotor 29.

It is contemplated by the present invention that the oppositely disposed vanes of the rotor be interconnected and staged in series flow relation. Such interconnection can be accomplished in different ways.

Referring, for example, to the form of the pump illustrated in FIGURE 10, there is shown a casing 11a having an inlet 33a so that fluid entering the inlet 33a will be impelled by a plurality of impeller pockets 71a and vanes 70a on one side of a rotor shown generally at 29a is pressurized through a runner or pumping duct 34a, is passing out of a first stage outlet shown at 40a. The fluid then passes through the hub portion of the rotor 29a and in this embodiment of the invention, the rotor is particularly characterized by axial through openings 74a. After passing through the openings 74a the fluid enters an inlet passage shown at 54a, whereupon it is acted upon by the impeller pockets and vanes on the other side of 75

the rotor 29a through the pumping duct or runner 49a and is then discharged through an outlet opening 48a.

In the form of the invention illustrated in FIGURES 11 and 12, the pump is of the same general organization and like reference numerals are used with the suffix *b* to designate like parts. In this form of the invention, however, the rotor is shown generally at 29b and may advantageously be constructed of a thin material such as sheet metal shaped to form a toroidally shaped article. For example, the rotor 29b has a radially outwardly extending wall 100 suitably fastened, for example, by spot welding or the like to a hub member 101 carried on a shaft 23b. The radial wall 100 terminates in an axially extending wall 102 spaced radially outwardly of the shaft 23b and arranged in general concentric relation to the axis of rotation thereof. The axial wall 102 is particularly characterized by having a plurality of circumferentially spaced struck-out pumping vanes 103 which in this form of the invention are struck-out to be shaped and arranged in outwardly projecting relation relative to corresponding openings 104. Thus, fluid discharged by the first stage through a first stage outlet 40b will pass through the openings 104 and will be assisted by the pumping action of the vanes 103 as the fluid is impelled from the first stage to the second stage. Thus, the fluid will enter the second stage inlet shown at 54b.

The axial wall 102 terminates in a second radial wall 106 which is offset in an axial direction in order to form a generally semi-toroidally shaped recess 107 and the rotor terminates in an outer peripheral edge 108.

In order to provide the second stage of the rotor, a separate piece of metal may be shaped to provide an annular trough-shaped article which is semi-toroidal in the cross-section and which is shown at 109. The article 109 may be connected in firm assembly to the correspondingly shaped portion of the main rotor by means of spot welding or other suitable fastening technique as shown at 110. Thus, the completely assembled rotor provides a toroid in which the vanes may be mounted for accomplishing the pumping action described in connection with the other forms of the pumping apparatus herein described. The outlet of the pump is shown at 48b.

In the form of the invention disclosed in FIGURES 1-9, the openings 74 constitute four circumferentially spaced passages having an irregular configuration shaped to develop the attributes of an airfoil or a fan in order to develop a pumping capacity. Thus, as the fluid passes through the openings 74, it is additionally impelled by the pumping action of the vane configuration, thereby assisting in pressurizing the fluid acted upon by the pump 10.

In operation, fluid enters the inlet 33 (or 33a or 33b) and is impelled by the impeller pockets 71 and the vanes 70 on one side of the rotor 29 through the pumping duct 34 whereupon the fluid is passed through the discharge passage 40 and thence through the internal passages 74 formed in the disk portion of the rotor 29. The fluid then enters the inlet passage 54 (or 54a or 54b) and is impelled by the impeller pockets and the vanes on the other side of the rotor 29 through the pumping duct 49 and the fluid is then discharged through the outlet opening 48. By virtue of such provision, it is possible to have a discharge pressure in the same magnitude as a positive displacement pump, while running in the speed magnitude of a so-called drag pump.

Although other modifications might be suggested by those versed in the art, it should be understood that I wish to embody within the scope of the patent warranted hereon all such modifications as reasonably and properly come within the scope of my contribution to the art.

I claim as my invention:

1. A fluid compressor of the drag type comprising, casing means forming two pumping chambers constituting a first stage and a second stage,

each having an inlet and an outlet, and an impeller rotor journaled for rotation in said casing means, and having a centrally disposed hub, a disk extending radially outwardly therefrom, and oppositely disposed vanes outwardly of correspondingly opposite sides of said disk for acting on fluid in each respective stage of said two pumping chambers, and an internal passage formed in and extending axially through said disk of said rotor and interconnecting said outlet of said first stage with said inlet of said second stage.

2. A fluid pump of the drag-type comprising, first and second cover members together forming a 15 pump casing,

one of said cover members having an inlet opening formed therein for connection to a source of fluid to be pumped,

said one of said cover members having formed 20 on the inner face thereof an annular vane duct connected to said inlet and having a discharge passage directed radially inwardly thereof, the other of said cover members having formed therein on the inner face thereof an annular 25 vane duct and having an inlet passage extending radially inwardly thereof and an outlet opening for connection to a point of utilization, a rotor in said casing having a drive shaft connected thereto and said drive shaft projecting out of said 30 casing for connection to a source of motive power, said rotor including annular recesses disposed on opposite axial sides of said rotor for registry with said vane ducts,

said rotor having a plurality of circumferentially 35 spaced slots each extending across a corresponding one of said annular recesses, and a vane in each slot to form with said recesses a plurality of impeller pockets, and axial passage means formed in said rotor disposed 40 to extend axially between said discharge passage and said inlet passage interconnecting said vane ducts in series staged flow relation.

3. A reentry compressor comprising, a casing having

an inlet cover formed with a peripheral flange, and having a centrally disposed bearing means, a shaft journaled in said bearing means and including means outside of said casing for connection to a motive source,

said inlet cover having formed therein a semi-toroidal circumferentially extending pumping duct having an inlet opening at one end and having a radially inwardly extending discharge passage at its opposite end,

said casing further including an outlet cover formed with a peripheral flange,

fastening means interconnecting said covers at said peripheral flanges to form said casing,

said outlet cover having formed therein a semi-toroidal circumferentially extending pumping duct having an outlet opening at one end and radially inwardly extending inlet passage at its opposite end,

and a generally disk-shaped rotor having a driven connection with said shaft for rotation inside of said casing,

said rotor having semi-toroidal circumferentially continuous vane ducts on opposite axial sides thereof disposed between said pumping ducts, each vane duct having a plurality of transversely extending circumferentially spaced vanes forming a plurality of impeller pockets in said vane duct to pump fluid from the inlet to the outlet of each respective pumping duct,

and means forming an internal axial through passage in said rotor interconnecting said radial discharge passage with said radial inlet passage, thereby interconnecting said pumping ducts on opposite sides of said disk-shaped rotor in series flow staged relation.

4. A reentry compressor comprising a casing having an inlet and an outlet and a pair of axially spaced annular circumferentially extending pumping ducts disposed therebetween, a rotor in said casing having oppositely disposed impeller means extending radially between and in register with said pumping ducts, and axial passage means in said rotor interconnecting the discharge portion of one of said pumping ducts with the inlet portion of the other of said pumping ducts, thereby staging the pumping ducts in series flow relationship.

5. A reentry compressor comprising casing means having a pair of separate pumping chambers spaced axially from one another, a rotor in said casing means extending radially between said pumping chambers and having impeller means extending axially from opposite faces thereof to cooperate with each corresponding pumping chamber,

said casing means having an inlet opening to one of said chambers and an outlet opening from the other of said chambers, and internal passage means formed in said casing means and including a passage formed in and extending through said rotor axially and interconnecting said chambers in series staging with one another.

6. A reentry compressor as defined in claim 5, said rotor comprising a generally disk-shaped member having an enlarged peripheral portion formed with vane ducts on opposite axial sides, each vane duct being substantially semi-cylindrical in cross section to form a trough-shaped recess,

and a plurality of circumferentially spaced vanes extending radially across said vane ducts to form plural impeller pockets.

7. A reentry compressor as defined in claim 6 and further characterized by said pumping chambers in said casing means comprising pumping ducts essentially semi-cylindrical in cross-sectional configuration and being disposed in confronting registry with said vane ducts.

50 8. A reentry compressor as defined in claim 7 and further characterized by said internal passage means comprising radially inwardly extending passages intersecting said pumping ducts and said axial through passage formed in said disk-shaped rotor inwardly of said peripheral portion of said rotor.

55 9. A reentry compressor comprising casing means having a pair of separate pumping chambers spaced axially from one another, a rotor in said casing means having impeller means extending axially from opposite faces thereof to cooperate with each corresponding pumping chamber,

said casing means having an inlet opening to one of said chambers and an outlet opening from the other of said chambers, and internal passage means formed in said casing means and extending through said rotor to stage said chambers in series with one another,

said rotor comprising a toroidally shaped article made of sheet form material and shaped to include a plurality of struck out portions forming impeller vanes with said internal passage means constituting openings underlying said vanes, thereby to additionally pressurize said fluid as it passes 75 through said passage means.

10. A reentry compressor as defined in claim 9 wherein in said rotor has an axially extending wall and said struck out portions are formed in said wall.

11. A fluid compressor as defined in claim 10 wherein said axial wall has a plurality of struck out portions circumferentially spaced to form openings and centrifugal pumping vanes for assisting in pressurizing the fluid passing therethrough.

12. A fluid compressor of the drag type comprising, 10

casing means forming two pumping chambers constituting a first stage and a second stage,

each having an inlet and an outlet, and an impeller rotor journaled for rotation in said

casing means, and having a centrally disposed hub, 15

a disk extending radially outwardly therefrom,

and oppositely disposed vanes outwardly of said disk for acting on fluid in each respective stage

of said two pumping chambers, 20

and an internal passage extending through said disk

8
of said rotor interconnecting said outlet of said first stage with said inlet of said second stage, said internal passage characterized by having formed therein pumping vanes to additionally pressurize the fluid passing therethrough.
